BROAD-BAND ANTENNA

Robert S. Wehner, Port Jefferson, N. Y., assignor
to Radio Corporation of America, a corporation
of Delaware

Application January 22, 1946, Serial No. 642,690

8 Claims. (Cl. 250—33)

1

The present invention relates to broad band antenna matching systems and more particularly to a system for adjusting the matching network when the antenna parameters are not at their optimum values for broad band response.

An object of the present invention is the provision of an additional series circuit in an impedance matching network for correcting any inadequacies in the parameters in the antenna for broad band operation.

A further object of the present invention is the provision of a short line section as a part of a broad band impedance matching section.

A further object of the present invention is the provision of an impedance matching system as aforesaid which is electrically and mechanically smooth.

A further object of the present invention is the provision of an impedance matching system as aforesaid which is adapted for the use of commercially available coaxial cable for the reactance elements.

Still another object of the present invention is the provision of an additional section in an impedance matching circuit for adjusting antenna parameters to yield their most favorable characteristics without requiring the antenna to be rebuilt.

A further object of the present invention is the provision of an impedance matching element whereby an antenna designed for use in one particular location may be adapted for use in a different location without rebuilding the antenna.

Still another object of the present invention is the provision of a short line section in an impedance matching network to vary the characteristics thereof for increasing the band with no adverse effects upon the field pattern of the associated antenna.

The foregoing objects and others which may appear from the detailed description are accomplished by providing in series between the antenna radiator itself and the impedance matching network, a short series section which has the effect of shifting resonance of the antenna toward higher frequencies while at the same time having little effect upon the antenna resistance.

This results in impedance characteristics looking into the short section terminated by the antenna which are similar to those of the original antenna except that the impedance level is higher.

The present invention will be more fully understood by reference to the following detailed

2

description which is accompanied by a drawing in which:

Figure 1 illustrates a form of the antenna to which the present invention is adapted to be applied, while

Figure 2 illustrates the application of the present invention to the antenna of Figure 1;

Figure 3 illustrates the antenna impedance and matching standing wave characteristics of the antenna of Figure 1, while

Figure 4 illustrates the antenna impedance and matched standing wave characteristics of the antenna as shown in Figure 2.

I have shown in my prior filed application, Serial Number 650,953, filed February 28, 1946, now Patent No. 2,485,177 issued Oct. 18, 1949, that a series resonant antenna which is shown in Figure 1 including the extending radiator portion 10 and the sleeve section 14 extending normal to the conductive ground plane GP may be matched to less than a 2:1 standing wave ratio on a transmission line TL of characteristics impedance Z_0 over very wide frequency bands. These frequency bands may be of the order of 2:1 in frequency spread or more. As described in the application referred to above the broad banding is accomplished by means of a simple series transformer matching section including the inner conductor 14 and outer sleeve 12 effectively connected in series between the transmission line TL and the radiator including radiator 10 and the outer surface of sleeve 12. Conductor 14 is connected between the lower end of radiator 10 and conductor 18 of the transmission line TL while sleeve 12 is connected electrically to ground plane GP and to the outer shell 16 of transmission line TL. The ratio of the diameter of conductor 14 to the inner diameter of sleeve 12 is so chosen that the characteristic impedance of this matching section is equal or nearly equal to the product of A and Z_0 where A is the desired maximum standing wave ratio. The impedance of the antenna is so adjusted by choosing the feed points, that is, the position of the junction between radiator rod 10 and sleeve 12 as to likewise be equal to or nearly equal to the product of A and Z_0 . As I have shown in the previous application, in broad banding an antenna to less than a 2:1 standing wave ratio on a 50 ohm line the best results are obtained by using a 100 ohm antenna in conjunction with a 100 ohm series impedance matching section. However, it sometimes happens that it is impossible or inconvenient to adjust the design parameters of the antenna so that its impedance

level is exactly equal to the optimum value of AZ_0 ohms; that is, it may be impossible to so choose the ratio of the diameter of rod 10 and sleeve 12 or the ratio of the lengths of rod 10 and sleeve 12 to exactly obtain an impedance level of AZ_0 ohms. Some loss of band width then results, this depending upon the sign and magnitude of the departure from the optimum value. If the impedance level is greater than AZ_0 ohms by not more than 20% little harm may be done and the antenna may be matched by transformer 12, 14 having an impedance of AZ_0 ohms over almost as wide a band as could be accomplished under the most favorable circumstances. However, if the impedance level of the antenna is less than AZ_0 ohms by even such a small factor as 5%, a serious loss in band width will result. This is due to the fact that if the resonant impedance of a series resonant antenna is appreciably less than AZ_0 ohms a real value for the electrical length of the AZ_0 transformer cannot be found such that the antenna will be matched over the entire frequency band in question. The electrical length of the matching section is indicated in Figure 1 as being of the order of 63 electrical degrees. This matching section, if it is long enough to match the inner resonant region, will be too long or too short to match the antenna to the transmission line at the two ends of the band. Previously, the only way out of this difficulty consisted in using a matching section of a characteristic impedance less than AZ_0 ohms and equal to or less than the impedance level of the antenna. This procedure results in a greater band width than could be obtained with a given low impedance antenna used with an AZ_0 ohm transformer, but the band width thus obtained is always less and sometimes a great deal less than what could be realized with the system if both the antenna and the impedance matching transformer had the proper impedance.

I have found that it is possible to remedy the deficiency of the antenna insofar as the impedance level is less than, rather than equal to or greater than AZ_0 ohms, by introducing between the antenna terminals at the junction place between radiator 10 and sleeve 12, a short length of Z_0 -ohm transmission line indicated in Figure 2 at 22 and 24. The outer sleeve 12 in Figure 2 has an additional inner sleeve 22 and/or there is a surrounding sleeve portion 24 around the inner central conductor 14 whereby the characteristic impedance of this section is reduced to 50 ohms, that is, to an impedance equal to the impedance of transmission line TL. The additional section has an electrical length such that the resonance of the antenna is shifted toward higher frequencies while at the same time it has relatively little effect upon the antenna resistance. Thus, impedance characteristics result, looking into section 22, 24 from the main impedance matching section 12, 14, which are very similar to those of the original antenna except that the impedance level is higher. The length of this section is so chosen as to make the system resonant at a frequency higher than the original resonant frequency and nearer the center of the desired band at which frequency the input resistance will be equal to or greater than AZ_0 ohms.

If Z_0 is the characteristic impedance of this short impedance matching section 22, 24 and θ its electrical length and if $Z=R+jX$ is the antenna impedance at any frequency higher than the original resonant frequency of the

antenna, then the impedance looking into section 22, 24 is given exactly by the transmission line quotation:

$$Z_{in} = \frac{Z_0 j Z_0 \tan \theta + Z}{Z_0 + j Z \tan \theta} \quad (1)$$

If θ is less than roughly one quarter radian (or 15 degrees) the input impedance is approximately given by the following:

$$Z_{in} = \frac{Z_0 j Z_0 \theta + Z}{Z_0 + j Z \theta} \quad (2)$$

From this equation it follows that the input impedance Z_{in} may be made non-reactive; that is, $X_{in}=0$ if θ is related to R and X by the following expression:

$$\theta = \frac{XZ_0}{X^2 + R^2 - Z_0^2} \quad (3)$$

Equation 3 may be used directly to determine the proper length of the short series 22, 24 since it gives θ in radians.

An example of the use of a short line section in broad banding antennas will now be given with reference to Figures 3 and 4.

Figure 3 illustrates in curve 31 the variation in input resistance to the antenna with a variation in frequency while curve 32 gives the variation in input reactance as frequency is varied. Curves 31 and 32 represent the actual measured input impedance of a coaxial aircraft antenna which was to be matched, preferably by means of a simple series transformer to less than a 2:1 standing wave ratio on a 50 ohm line over the range extending from 190 to 420 megacycles.

The necessary condition for the matching of an impedance X to less than A:1 standing wave ratio on a main line of characteristic impedance Z_0 over a band of frequencies by means of a simple transformer of impedance Z_m is that the impedance Z must, at all frequencies in the band, lie on or within the $A_m:1$ circle of the line Z_m where A_m is given by the relationship

$$A_m = Z_m \left(\frac{A}{Z_0} \right)$$

This condition sets a lower limit to the characteristic impedance of the transformer required to match a given set of antenna data over a given range, since the entire impedance curve in the complex plane must lie within the $A_m:1$ standing wave ratio circle of a line of that characteristic impedance. The area of this circle, that is, the range of impedance which it includes, is directly proportional to the square of Z_m . The minimum characteristic impedance of a transformer capable of matching an impedance $R+jZ$ to less than 2:1 standing wave ratio on a 50 ohm line is given by the following equation:

$$Z_m = \frac{25(R^2 + X^2 - 25R)}{r - 25} \quad (4)$$

The most difficult point to match in the impedance characteristic of a series resonant antenna is its low frequency limit, since that point is always characterized by the lowest resistance and the largest, relative to the resistance, reactance. The value of Z_m required to match the antenna of Figure 1 whose characteristics are shown in Figure 3 over the range of 190 to 420 megacycles may be found by substituting the values of R and X for 190 megacycles in Equation 4. It will be seen that at 190 megacycles R and X are equal respectively to 42 and 76 to -76 ohms. Therefore, a transformer hav-

ing a minimum characteristic impedance of the order of 100 ohms is required.

But, it will be noted that the resonant resistance of 274 megacycles of the antenna is only 92 ohms, a value which is appreciably less than 100, the characteristic impedance of the transformer. A resistance of 92 ohms lies within the 2:1 standing wave ratio circle of the 50 ohm line by itself, but when a 100 ohm transformer is applied to the antenna, the region near resonance, where the antenna is matched initially, becomes mismatched if the length of the transformer is such as to match the low and high frequency ends of the band; that is, 92 ohms is sufficiently smaller than 100 ohms that a real value of the electrical length of a 100 ohm transformer 12, 14 cannot be found such that the antenna is matched over the entire band. The best possible band width obtainable with the antenna of Figure 1, determined by trial and error, is that indicated by the standing wave ratio characteristic plotted in curve 33 of Figure 3. This shows the voltage standing wave ratio on a 50 ohm line looking into a 63 degree long 100 ohm transformer terminated by the antenna 10, 12. While the antenna is satisfactorily matched at the high and low frequency ends of the pass bands, it is mismatched as shown by the cross hatched portion 35, over some 65 megacycles in the vicinity of resonance to an extent greater than the allowable maximum.

This situation may be remedied by means of the short line section described above with reference to Figure 2. It is proposed that resonance be shifted from 250 megacycles, where the resistance is only 92 ohms, to mid band or 300 megacycles where the antenna resistance is substantially greater than 100 ohms at 300 megacycles. The antenna has a resistance of 110 ohms with a reactance equal to +22 ohms. If these values are substituted in the Equation 3, it is found that a section of 50 ohm line only .11 radians long, or 6.3 degrees, at 300 megacycles has the desired effect. The impedance looking into this section terminated in the antenna is shown by curves 41 and 42 in the upper part of Figure 4. These impedance characteristics, since the resonant resistance is higher than the critical value of 100 ohms, are readily matched over the entire desired band by means of a 100 ohm transformer. The standing wave ratio characteristic for a 50 ohm line terminated in this matched impedance is plotted in curve 42 in Figure 4. It is evident here that the use of the short section of main line between the antenna terminals has resulted in standing wave ratio of less than 2:1 over the desired frequency range.

For wide band operation the series line section actually reduces the rate of variation of reactance with frequency while the use of a series condenser in its place may increase it. This effect is shown for the case of the antenna described above in the following table:

antenna-condenser system but that the latter requires much higher impedance transformer than the 100 ohm one used in the example to make a match possible. The low frequency impedance with the condenser, namely 42-j111 ohms, is much harder to match to the stated standard than is the 36-j68 ohms impedance at the low frequency extreme of the antenna-line-section system, the former requiring a 138 ohm (from Equation 4) transformer, which value is not only impractically high from the point of view of physical realization, but also is so high as to defeat the original purpose of using the condenser.

The intermediate line section of the same characteristic impedance as that of the main line TL tends to reduce the necessary length of the main series transformer section 12, 14 by an amount greater than the length of the intermediate section 22, 24. Consequently, the overall length of the antenna and matching section is not any greater than that of the simple system shown in Figure 1. In view of the gain in performance effected by the series section this fact constitutes a big advantage of this method, particularly as compared to the bulky series shunt combination matching section heretofore used. In practical applications, where it is often necessary to build the matching section into the antenna structure itself in order to obtain a single self contained radiating unit, space is at a premium.

At low frequencies, where it may be convenient to use lengths of commercially available cable for both the transformer and the short series line section, use of the short series line section involves nothing more than the introduction of a short length of the main line cable between the transformer and antenna terminals. At higher frequencies, the short section may be realized by slipping an appropriately long piece of metal tubing either within the sleeve 12 or a short section of smaller diameter metal tubing around the inner conductor 14 nearest the antenna feed point.

While the foregoing description has been predicated on the use of coaxial line sections it should be understood that the short series line section may equally well be employed with a balanced transmission line and antenna system if desired.

The present invention has a further application in antennas of such nature that it is difficult to design them to have the proper impedance level initially and where, if a mistake in judgment should occur, it is practically impossible to readjust the antenna parameters to yield more favorable characteristics without entirely rebuilding the antenna. Typical antennas of this type are large surface area sleeve antennas of streamline shape. In these antennas, because of the necessity for maintaining a special shape and surface contour, none of the critical dimensions

System	Resistance at 190 mc.	Reactance at 190 mc.	Reactance at 300 mc.	Average Slope, Reactance in ohms/megacycle
Original Antenna	42	-76	22	0.89
Antenna plus short line section	36	-68	0	0.62
Antenna plus series condenser	42	-111	0	1.01

It will be noted that not only is the antenna-line section combination much flatter than the

can be changed once the structure is built. If such an antenna should happen to have an im-

pedance level lower than the optimum value, it is obviously much easier to correct the defect by the simple addition of a short sleeve in the feed line to produce the series matching section than it would be to rebuild the whole antenna.

Also, the short series line section may often find use in the case of matching the driving element in antenna arrays, corner reflectors, and paraboloids. In such systems, field pattern considerations over a band of frequencies may be such as to cause the input impedance level of the driver antenna to be much less than the optimum value for the desired band width. The short series line section of Figure 2 may be used to improve impedance characteristics with no adverse effects on the field pattern.

Furthermore, in aircraft radio, it is sometimes necessary to use an antenna designed for one particular location in either a different location on the same airplane or corresponding location on a larger airplane. The impedance level of series-resonant stub and whip antennas is very sensitive to the radius of curvature of the surface upon which they are mounted, being higher the smaller the radius relative to the operating wavelength. Some broad band aircraft antennas depend for their band width upon the high impedance level resulting when these antennas are mounted on the relatively sharply curved fuselage of a small airplane. If such antennas are then moved to flatter surfaces, the impedance level drops and so does the band width. In many cases it is possible to compensate for this loss of band width by means of the short line section as described above with the result that it is then possible to use a given broad band antenna in widely different locations with no design changes other than the insertion of the short additional line section between the antenna terminals and the matching section.

While I have illustrated a particular embodiment of the present invention, it should be clearly understood that it is not limited thereto since many modifications may be made in the several elements employed and in their arrangement and it is therefore contemplated by the appended claims to cover any such modifications as fall within the spirit and scope of the invention.

What is claimed is:

1. In a broad band antenna system including a radiator extending normally to a conductive ground plane, a high impedance matching section having an impedance value of AZ_0 ohms where A is the maximum allowable standing wave ratio and comprising concentric conductors coaxially arranged with respect to said radiator, the inner conductor of said matching section being connected to said radiator and the sleeve conductor being connected to said ground plane at a point intermediate its length, and a coaxial transmission line having an impedance value of Z_0 ohms and comprising a sheath connected to the sleeve conductor and a center conductor connected to the inner conductor of said matching section, the impedance level of said radiator being less than AZ_0 ohms, a further matching section comprising a length of coaxial transmission line having an impedance value of Z_0 ohms and an electrical length of substantially six degrees interposed between said radiator and said high impedance matching section to transform the impedance level of said radiator to a value at which said high impedance matching section will be effective over said broad-band.

2. In a broad band antenna system including

a radiator extending normally to a conductive ground plane, a high impedance matching section comprising concentric conductors coaxially arranged with respect to said radiator, the inner conductor of said matching section being connected to said radiator and the outer conductor being connected to said ground plane at a point intermediate its length, and a coaxial transmission line having a sheath connected to the outer conductor of said matching section and a center conductor connected to the inner conductor of said matching section, the impedance level of said radiator being lower than optimum for broad band matching with said high impedance matching section, a coaxial transmission line section of the same characteristic impedance as that of the first said coaxial transmission line interposed between said radiator and said high impedance matching section and having an electrical length substantially one-tenth that of said high impedance matching section thereby to shift the resonance of said radiator to a higher frequency without affecting its impedance characteristics.

3. In a broad band antenna system including a radiator extending normally to a conductive ground plane, a high impedance matching section comprising concentric conductors coaxially arranged with respect to said radiator, the inner conductor of said matching section being connected to said radiator and the outer conductor being connected to said ground plane at a point intermediate its length, and a coaxial transmission line having a sheath connected to the outer conductor of said matching section and a center conductor connected to the inner conductor of said matching section, the impedance level of said radiator being lower than optimum for broad band matching with said high impedance matching section, a conductive element surrounding said inner conductor and being connected to one of said conductors adjacent said radiator and said high impedance matching section to transform the impedance level of said radiator to a value at which said high impedance matching section will be effective over said broad band.

4. In a broad band antenna system including a radiator extending normally to a conductive ground plane, a high impedance matching section comprising concentric conductors coaxially arranged with respect to said radiator, the inner conductor of said matching section being connected to said radiator and the outer conductor being connected to said ground plane at a point intermediate its length, and a coaxial transmission line having a sheath connected to the outer conductor of said matching section and a center conductor connected to the inner conductor of said matching section, the impedance level of said radiator being lower than optimum for broad band matching with said high impedance matching section, a pair of hollow, cylindrical, conductive elements concentrically arranged within said high impedance matching section at the end adjacent said radiator, one of said conductive elements having the inner surface thereof coincident with said inner conductor and the outer surface of the other being coincident with the inner surface of said outer conductor to constitute a further impedance matching section to transform the impedance level of said radiator to a value at which said high impedance matching section will be effective over said broad band.

5. In a broad band antenna system including a

radiator of given diameter extending normally to a conductive ground plane, a high impedance matching section having an impedance value of AZ_0 ohms where A is the maximum allowable standing wave ratio and comprising concentric conductors coaxially arranged with respect to said radiator, there being an overlap between said radiator and the sleeve conductor of said matching section, the inner conductor of said matching section having a diameter smaller than said given diameter and being connected to said radiator, said sleeve conductor being connected to said ground plane at a point intermediate its length, and a coaxial transmission line having an impedance value of Z_0 ohms and comprising a sheath connected to the sleeve conductor and a center conductor connected to the inner conductor of said matching section, the impedance level of said radiator being less than AZ_0 ohms, the relative diameters of said radiator and said sleeve conductor having values providing an impedance value of Z_0 ohms interposed between said radiator and said high impedance matching section to shift the resonance of said radiator to a higher frequency without affecting its impedance characteristics.

6. In a broad band antenna system including a radiator extending normally to a conductive ground plane, a high impedance matching section having an impedance value of AZ_0 ohms where A is the maximum allowable standing wave ratio and comprising concentric conductors coaxially arranged with respect to said radiator, the inner conductor of said matching section being connected to said radiator and the sleeve conductor being connected to said ground plane at a point intermediate its length, and a coaxial transmission line having an impedance value of Z_0 ohms and comprising a sheath connected to the sleeve conductor and a center conductor connected to the inner conductor of said matching section, the impedance level of said radiator being less than AZ_0 ohms, means to alter the spacing between said conductors of said high impedance matching section for an electrically short distance at the end thereof adjacent said radiator to render the impedance value thereat substantially equal to Z_0 ohms to transform the impedance level of said radiator to a value at which said high impedance matching section will be effective over said broad band.

7. In a broad band antenna system including a radiator extending normally to a conductive ground plane the outermost extremity of said radiator being a quarter wavelength from said ground plane, a high impedance matching section having an impedance value of AZ_0 ohms where A is the maximum allowable standing

wave ratio and comprising concentric conductors coaxially arranged with respect to said radiator, the inner conductor of said matching section being connected to said radiator and the sleeve conductor being connected to said ground plane at a point intermediate its length, and a coaxial transmission line having an impedance value of Z_0 ohms and comprising a sheath connected to the sleeve conductor and a center conductor connected to the inner conductor of said matching section, the impedance level of said radiator being less than AZ_0 ohms, a further matching section having an impedance value of Z_0 ohms interposed between said radiator and said high impedance matching section to transform the impedance level of said radiator to a value at which said high impedance matching section will be effective over said broad band, said high impedance matching section having a length of substantially 63 electrical degrees and the length of said further matching section being substantially one-tenth of that value.

8. A broad band antenna structure including a radiator extending normally to a conductive ground plane, a sleeve coaxially arranged in end-to-end relationship with said radiator, there being an overlap between said radiator and said sleeve, said sleeve being connected to said ground plane at a point intermediate its length, a conductor within said sleeve connected to said radiator, said conductor and said sleeve constituting a high impedance matching section, the spacing between said sleeve and said radiator at said overlap being less than the spacing between said sleeve and said conductor therewithin, a coaxial transmission line comprising a center conductor and a sheath, said sheath being connected to said sleeve and said center conductor being connected to said conductor within said sleeve, whereby the impedance level of said radiator is lower than optimum for broad band matching with said high impedance matching section, and the impedance level of said overlap is a value to transform the impedance level of said radiator to a value at which said high impedance matching section will be effective over said broad band.
